CENTRIFUGAL SUMP PUMP

Charles B. Wells, Feasterville, Pa., assignor to Hartell,
Inc., Huntingdon Valley, Pa., a corporation of Penn-
sylvania

Filed May 26, 1964, Ser. No. 80,151

Term of patent 14 years

(Cl. D65—1)

Fig. 1.

Fig. 2.

FIG. 1 is a side perspective view of the centrifugal sump pump embodying my new design;

FIG. 2 is a fragmentary, perspective view thereof of the opposite side from that shown in FIG. 1;

FIG. 3 is a bottom plan view thereof;

FIG. 4 is a front elevational view; and

FIG. 5 is a rear elevational view thereof.

The conventional screen pattern present in FIG. 3 is fragmentarily shown for convenience of illustration and is understood to continue throughout the area enclosed by broken lines. The large pipe has been fragmentarily shown in FIG. 2 for convenience of illustration.

I claim:

The ornamental design for a centrifugal sump pump, as shown and described.
